UNITED STATES PATENT OFFICE

2,113,614

LEATHER PRINTING AND TIPPING
MACHINE

Paul Dornbusch, Krefeld, Germany

Original application June 29, 1935, Serial No.
29,089. Divided and this application August
20, 1936, Serial No. 97,054

8 Claims. (Cl. 101—150)

This is a divisional application of my application for United States Letters Patent, filed on June 29, 1935, Serial No. 29,089 granted on October 20, 1936 as Patent No. 2,058,006.

5 This invention relates to new and useful improvements in methods and devices for printing and tipping whole hides.

More particularly, the invention proposes a method characterized by continuously passing a 10 web of paper or other similar carrier material, between a printing drum and a printing cylinder, and feeding or supporting whole hides on said web to pass between the printing drum and the printing cylinder so as to be printed.

15 A feature of the invention resides in the fact that the continuously passing web normally protects the printing drum from the printing cylinder at areas between or to the sides of the hides.

A further object of the invention is to tension 20 the whole hides as they are passed between the printing drum and the printing cylinder so as to hold them smooth during the printing operation.

Still further, the invention contemplates the 25 construction of a device or machine which is adapted to print whole hides and which is also capable of applying secondary colors upon the hides. In all old methods and devices for printing whole hides it has been customary to apply secondary colors by hand.

30 Still further, the invention also proposes the construction of a controlled ink supply device which has a doctor blade engaging across the printing cylinder and arranged to substantially form one side of a pan for holding and directing 35 the ink on the printing cylinder. Furthermore, an arrangement is proposed for oscillating said doctor blade to more evenly distribute the ink, and to maintain the straight edge of the doctor blade by more even wear thereof.

40 It is a further object of this invention to provide a machine as mentioned which is characterized by a frame, a printing drum mounted on the frame, a printing cylinder adjustably mounted on the frame and adapted to cooperate with the printing drum to print hides passed therebetween, a controlled ink supply for the printing cylinder, and a hide carrying agent for carrying 45 hides between the printing drum and printing cylinder, and adapted to protect the printing drum from ink when a hide passes out from between the printing drum and printing cylinder.

45 A feature of the machine is that the printing cylinder may be of various types, such as the surface printing type, or of the intaglio type. It 50 may be photoengraved, milled, or may be master

die. The printing cylinder may be adapted to apply secondary colors on raised portions of the hide (tipping). It may be a screen cylinder.

Another object of the invention is the construction of a device as described which is simple and durable and which may be manufactured and sold at a reasonable cost.

For further comprehension of the invention, and of the objects and advantages thereof, reference will be had to the following description and accompanying drawings, and to the appended claims in which the various novel features are more particularly set forth.

In the accompanying drawings forming a material part of this disclosure:—

Fig. 1 is a perspective view of a device constructed according to this invention.

Fig. 2 is an end elevational view of Fig. 1 looking from the right hand end.

Fig. 3 is a front elevational view of Fig. 1.

Fig. 4 is a fragmentary perspective view of a portion of the adjusting screw which controls the pressure of the doctor blade.

Fig. 5 is a fragmentary sectional view taken on the line 5—5 of Fig. 2.

The leather printing and tipping machine, according to this invention, comprises a frame consisting of side portions 10a and 10b held in fixed spaced positions by several tie rods 10c. A printing drum 11 is mounted in bearings 12 on side portions of the frame members 10a and 10b. The arrangement is such that reduced ends of the drum 11 merely rest upon the bearings 12, which are semi-cylindrical, so that the drum may be lifted out of the machine when desired. The printing drum 11 is held against normal displacement by a printing cylinder 13 which has reduced ends supported in bearings 14 located vertically above the bearings 12. The bearings 14 are adjustably mounted on the side members 10a and 10b of the frame and are held in adjusted positions by several vertical screws 15 which threadedly engage through the upper ends of the side members 10a and 10b of the frame. The free ends of the screws 15 are provided with handles 15a by which they may be easily turned. The lower ends of the screws rotatively connect with the housings of the bearings 14 so that when the screws are rotated the bearings 14 move vertically upwards or downwards.

The base ends 14' of the housings of the bearings engage in vertical grooves 10' of the frame to firmly guide the bearings in their movements to the various adjusted positions. The screws 15 also serve as a means for controlling the space

between the printing cylinder and the printing drum. Furthermore, they provide for the control of the pressure between these parts, or elements of materials passed through these parts, during the operation of the machine.

The printing cylinder 13 is engraved, or in any other manner formed with a printing design or pattern. A controlled ink supply is associated with the printing cylinder 13 and comprises, essentially, a doctor blade 16 mounted upon a flat body 17 which is extended at an angle to one side of the printing cylinder, in which the ink may be placed. The ends of this space are closed by end pieces 18. The edge of the doctor blade 16 which engages against the printing cylinder is very sharp and straight so that there is a fine supply of ink. A means is provided for holding the doctor blade 16 in various positions and comprises several adjusting screws 19 rotatively connected with the doctor blade and threadedly engaged through bushings 20 upon the flat body 17. These screws are provided with handles 21 by which they may be conveniently turned. At the ends, the flat body 17 is formed with lugs 22 upon which the end pieces 18 are attached by screws 23. The end pieces 18 have arcuate shaped portions of felt material or similar material (indicated by reference numerals 24) engaging against the side of extension portions of the printing cylinder.

The flat body 17 is swivelly and adjustably held so that the edge of the doctor blade may be engaged against the side of the printing cylinder under suitable pressure. More particularly, the flat body 17 has offset bosses 25 at its ends from which the offset studs 26a project. The studs 26a connect with returning portions 27b on which there is a trunnion 26. This trunnion engages in bearings 27c which are adjustably mounted upon the side members 10a and 10b of the frame. Arms 27 are attached fixedly on the blocks 27b and extend over the printing cylinder. The latter ends of the arms 27 are of fork shape (see Fig. 4) and support bushings 28. These bushings 27c are pivotally supported by a trunnion 29 engaging the arms of the fork. An adjustment screw 30 threadedly engages through each bushing. Handles 31 are mounted upon the top ends of the adjustment screws by which they may be turned. Blocks 32 are rotatively mounted upon the bottom ends of the screws and have bottom faces which are in intimate contact with reduced ends 13a of the printing cylinder.

A mechanism is provided for oscillating the flat body 17 to oscillate the doctor blade 16, and comprises an arm 34 fixedly mounted on an extended end of one of the elements of the trunnion 26. This arm 34 has a slot 34' in its end. This slot engages a circular cam disc 35 mounted upon one end of the printing cylinder 13. The cam disc 35 may be clearly seen in Fig. 2 to be a flat disc arranged at an inclination, and it will be understood that as the disc is turned the trunnion element 26 will be oscillated. Of course, the oscillation includes the flat body 17 and the doctor blade 16.

The bearings 27c are adapted to be horizontally adjusted. These bearings are slidably mounted upon brackets 27a, which in turn are fixedly mounted on the side members of the frame. Screws 37 are threadedly engaged through portions of the brackets 27a and rotatively connect with the bearings 27c so that when the screws are turned the bearings move horizontally forwards or rearwards. The

screws 37 are provided with handles 37' by which they may be conveniently turned.

A hide carrying agent in the form of a web 40 is adapted for carrying hides between the printing cylinder and the printed drum, and to simultaneously protect the printing drum from ink from the printing cylinder at spaces which are not covered by the hides. The web 40 is part of a roll 40a of sheet material mounted upon the front of the machine and connecting with a roll 40b mounted upon the back of the machine. The rolls 40a and 40b of sheet material are mounted upon shafts 41 and 42 respectively. These shafts have intermediate portions with cone-shaped members 43 thereon to facilitate holding the rolls.

The shafts 41 and 42 have reduced ends 41' and 42' respectively, which engage in bearings 44 mounted on the side members of the frame. The shaft 41 is adapted to be restrained or braked to prevent the material from the rolls unwinding too rapidly and is also equipped to be adjusted to obtain true unwinding. A gear 45 is mounted upon one end of the shaft 41 and meshes with a pinion 46 mounted upon a drum 47 of a brake which includes brake bands 48 controlled by an adjusting screw 49. Further details of the brake will not be given in this specification as it forms no part of the invention and brakes of this type are generally known. The screw 49 may be turned in one direction or the other to tighten or loosen the brake which restrains the rolls 40a from unwinding too rapidly. The other end of the shaft 41, which is supported by the bearing 44 is adjustable in a horizontal direction. The bearing 44 is adjustably mounted on a bracket 50 mounted on the side member of the frame. A screw 51 threadedly engages the bracket and rotatively engages the bearing so that the bearing may be adjusted horizontally.

A means is provided for driving and controlling the machine. This means consists of a pulley 52 freely rotative on a stud shaft 52a rotative on the side member 10a of the frame. A coupling is associated with the stud shaft 52a and the pulley 52 for coupling these parts together. This coupling comprises a screw 53 adjustably mounted on a member 54 adapted to engage a cone-shaped member 55 spliced on the stud shaft 52a to transmit rotations. The cone-shaped member 55 has a grooved end 55' which is engaged by a lug 56 from a control handle 57. This control handle is pivotally mounted intermediate of its ends by a bolt 58 upon a support rod 59 mounted on the side member of the frame. The lever 57 may be pivoted from either end, that is, the front or the back of the machine to engage or disengage the clutch. A gear 60 is mounted upon the stud shaft 52a and meshes with a gear 61 rotatively supported on the side member 10a of the frame. This gear 61 is coaxially connected with a sprocket 62 and a pinion 63. The pinion 63 meshes with a large gear 64 fixed on the end of the printing drum 11. The sprocket 63 connects with a chain 65 which connects with another sprocket 66 also mounted on the side member 10a of the frame. The sprocket 66 is fixed coaxially with a small gear 67 meshing with a gear 58 fixed upon the shaft 42. Thus, the shaft 42 is driven to wind on the web drawn off from the roll 40a. The far end of the printing drum 11 is equipped with a gear 61' meshing with a gear 60' on the far end of the printing drum 13.

The web 40 is arranged at an inclination relative to the printing cylinder and the printing drum 75

so that a hide may be placed thereon and be frictionally maintained in relative position and be passed through between the printing cylinder and the printing drum to be printed. In Fig. 1 a hide 70 is shown resting upon the web 40 and being drawn through the printing machine. A tensioning device is provided for smoothing out the hide. This device consists of a frame composed of several parallel bars 72a, 72b, 72c, which are supported at their ends upon side arms 73. This frame has a trunnion 74, the elements of which rotatively engage in bearings 75 supported upon the side members of the frame. The web 40 is laced between the bars 72a, 72b and 72c, as clearly indicated in Fig. 2.

The operation of the device is as follows:—

A prime mover is connected with the pulley 52. Rotations from the pulley 52 are transmitted to the printing drum 11 and to the gear 61', the gear 60' and the printing cylinder 13. The gear 60' meshes with the gear 61' so that the printing drum rotates simultaneously with the rotation of the printing cylinder. If it is desired, the gears 60' and 61' may have their pitch diameters differing slightly from the diameter of the printing cylinder and the printing drum so that the peripheral speeds of the rotating printing cylinder and printing drum at the contact areas are slightly different. This produces friction or pull on the material (the web) so that the design has a blur on it. If it is desired to print without the blur (producing a different pattern) it is merely necessary to have the gears 60' and 61' of the correct size to produce non-friction rotation of the printing cylinder and the printing drum.

The rotations from the pulley 52 are transmitted to unwind the web 40 from the roll 49a and to wind this web on the roll 49b. The web 40 serves to protect the printing drum from ink from the printing cylinder at areas not protected by the hide (see Fig. 1). Furthermore, the web 40 acts as a carrying agent for the hide to carry the hide between the printing cylinder and the printing drum. The printed hide will be discharged at the back of the machine. When the complete web has been wound upon the roll 49b, it is interchanged with the roll 49a. The gear 68 will then be in the position of the gear 45 and mesh with the small gear 46 of the braking device.

The cam 35 will oscillate the flat body 17 and the parts carried by the flat body. These parts include the doctor blade 16 and the end closures 18. Thus, the ink carried by the ink pan composed of the doctor blade and the end closures will be oscillated. The felt portions 24 will ride back and forth along smooth ends 13 of the printing cylinder. The ends 18 have extending portions 18' which may be used as handles for holding the ink control device when it is placed upon and removed from the machine. Since the arms 27 are carried by the blocks 27b, these arms will move along with the oscillating motion previously described. The members 32 will merely slide along the portions 13a of the printing cylinder.

The pressure between the doctor blade and the printing cylinder may be controlled by operation of the handles 31. As the bushings 28 move up or down upon the screws 30, the doctor blade will tend to pivot about the trunnion 26. This controls the pressure against the printing cylinder. The pressure against the printing cylinder may also be controlled in a horizontal direction by the operation of the screws 31. The screws 19 are used to properly align the doctor blade upon the printing cylinder. If one end or the other end

of the doctor blade needs to be adjusted, one or the other of the screws 19 may be turned to accomplish the adjustment.

While I have illustrated and described my invention with some degree of particularity, I realize that in practice various alterations there-in may be made. I therefore reserve the right and privilege of changing the form of the details of construction or otherwise altering the arrangement of the correlated parts without departing from the spirit or the scope of the appended claims.

Having thus described my invention, what I claim as new, and desire to secure by United States Letters Patent is:—

15

1. In a device of the class described, a printing cylinder adjustably mounted on a frame and cooperable with a printing drum to print material passed there between, a controlled ink supply for the printing cylinder comprising a flat body, a doctor blade adjustably mounted upon the body to engage against the printing drum, means for pivotally supporting said body, and an arm connected with the body and adjustably held relative to the printing cylinder for controlling the pressure of the doctor blade against the cylinder, and means for oscillating said flat body.

2. In a device of class described, a printing cylinder adjustably mounted on a frame and cooperable with a printing drum to print material passed there between, a controlled ink supply for the printing cylinder comprising a flat body, a doctor blade adjustably mounted upon the body to engage against the printing drum, means for pivotally supporting said body, and an arm connected with the body and adjustably held relative to the printing cylinder for controlling the pressure of the doctor blade against the cylinder, and means for oscillating said flat body, comprising a cam engaging a rotating element and cooperating with an arm mounted with the flat body.

3. In a device of the class described, a printing cylinder, a doctor blade engaging said printing cylinder and extending at an angle to the side thereof dividing off a space between these parts, end piece members extending between said doctor blade and said printing cylinder for closing the ends of said space to form a reservoir for holding printing ink for said printing cylinder, and means for reciprocating said doctor blade.

4. In a device of the class described, a printing cylinder, a doctor blade engaging said printing cylinder and extending at an angle to the side thereof dividing off a space between these parts, end piece members extending between said doctor blade and said printing cylinder for closing the ends of said space to form a reservoir for holding printing ink for said printing cylinder, and means for reciprocating said doctor blade and end piece members as a unit for maintaining the capacity of said reservoir constant and simultaneously causing the doctor blade to reciprocate relative to said printing cylinder as is required for good operation of the doctor blade.

65

5. In a device of the class described, a printing cylinder, a body extending longitudinally of said printing cylinder dividing off a space with the side of said printing cylinder, end piece members mounted on said body and extending between said body and said printing cylinder for closing the ends of said space, a doctor blade mounted on said body and engaging the side of said printing cylinder and extending between the

70

75

body and the printing cylinder for closing the bottom of said space to form a reservoir for holding printing ink for said printing cylinder, and means for reciprocating said body and the parts mounted thereon for maintaining the capacity of said reservoir constant and simultaneously causing the doctor blade to reciprocate relative to the printing cylinder as is required for good operation of the doctor blade.

6. In a device of the class described, a printing cylinder, a body extending longitudinally of said printing cylinder dividing off a space with the side of said printing cylinder, end piece members mounted on said body and extending between said body and said printing cylinder for closing the ends of said space, a doctor blade mounted on said body and engaging the side of said printing cylinder and extending between the body and the printing cylinder for closing the bottom of said space to form a reservoir for holding printing ink for said printing cylinder, and means for reciprocating said body and the parts mounted thereon for maintaining the capacity of said reservoir constant and simultaneously causing the doctor blade to reciprocate relative to the printing cylinder as is required for good operation of the doctor blade, a trunnion for pivotally supporting said body, and means for pivotally adjusting said body for controlling the pressure of said doctor blade against said printing cylinder.

7. In a device of the class described, a printing cylinder, a body extending longitudinally of said printing cylinder dividing off a space with the side of said printing cylinder, end piece members mounted on said body and extending between said body and said printing cylinder for closing the ends of said space, a doctor blade mounted on said body and engaging the side of said printing cylinder and extending between the body and the printing cylinder for closing the bottom of said space to form a reservoir for holding printing ink for said printing cylinder, and means for reciprocating said body and the parts mounted thereon for maintaining the capacity of

said reservoir constant and simultaneously causing the doctor blade to reciprocate relative to the printing cylinder as is required for good operation of the doctor blade, a trunnion for pivotally supporting said body, and means for pivotally adjusting said body for controlling the pressure of said doctor blade against said printing cylinder, comprising a radial arm secured on said body, a bushing swivelly mounted on said radial arm, a screw threadedly engaging through said bushing, and a block removably mounted on said screw and bearing against a portion of said printing cylinder.

8. In a device of the class described, a printing cylinder, a body extending longitudinally of said printing cylinder dividing off a space with the side of said printing cylinder, end piece members mounted on said body and extending between said body and said printing cylinder for closing the ends of said space, a doctor blade mounted on said body and engaging the side of said printing cylinder and extending between the body and the printing cylinder for closing the bottom of said space to form a reservoir for holding printing ink for said printing cylinder, and means for reciprocating said body and the parts mounted thereon for maintaining the capacity of said reservoir constant and simultaneously causing the doctor blade to reciprocate relative to the printing cylinder as is required for good operation of the doctor blade, a trunnion for pivotally supporting said body, and means for pivotally adjusting said body for controlling the pressure of said doctor blade against said printing cylinder, comprising a radial arm secured on said body, a bushing swivelly mounted on said radial arm, a screw threadedly engaging through said bushing, and a block removably mounted on said screw and bearing against a portion of said printing cylinder.

PAUL DORNBUSCH. 45
